UNITED STATES PATENT OFFICE.

WILLIAM LOUDEN, OF FAIRFIELD, IOWA.

MOLD FOR MANGER-CURBS.

1,228,937.

Specification of Letters Patent. Patented June 5, 1917.

Application filed August 13, 1913. Serial No. 784,541.

To all whom it may concern:

Be it known that I, WILLIAM LOUDEN, residing at Fairfield, in the county of Jefferson and State of Iowa, have invented a new and useful Improvement in Molds for Manger-Curbs, of which the following is a specification.

My invention relates to molds for manger-curbs for cattle-stalls, and it consists of a form comprising a core member to set at any point between the boards which are used for the mold in constructing the curb so that when the cement is poured in between the boards the place occupied by the form will not be filled with the cement but will be left with a cut-out or recess corresponding to the shape of the form; also in other features hereafter set forth and more particularly defined by the claims.

20 In the accompanying drawings:

Figure 1 is a perspective view of one of my forms with a stanchion anchor attached;

Fig. 2 is a vertical transverse section on line 2—2 of Fig. 1 looking in the direction 25 of the arrow, the mold boards being placed at the sides of the cut-out form;

Fig. 3 is a side view of a portion of a manger curb with a cut-out as made by my form, and showing the attachment of the 30 stanchion and stall posts;

Fig. 4 is a vertical longitudinal section of the form with another style of stanchion anchor attached, and showing a portion of the rear mold board for the curb;

35 Fig. 5 is the same showing still another style of stanchion anchor; and

Fig. 6 is a vertical transverse section on lines 6—6 of Fig. 5, the mold boards on both sides being shown.

40 Referring to the drawings, A represents my cut-out form in general which as shown, comprises two side boards S, a bottom board B, a sheet metal bottom and ends D, and two top cleats C.

45 When the bottom board B is used the sheet-metal bottom D (which includes the ends up to the cleats C) are tacked to the cleats C, the edges of the boards S and also to the bottom board B and may be made of

50 two pieces. The bottom board B, however, may be discarded and a single piece of sheet-metal may be used which will be tacked to the cleats C and the edges of the side boards S.

55 In using my cut-out form it is set in between the mold boards E where the cut-out

is to be made so as to form what may be called a core and the plastic cement being poured in between the mold boards, cannot run into the space occupied by the form. 60 Consequently there will be what is known as a cut-out I in the upper edge of the curb H as shown by Fig. 3. These cut-outs are desirable where the stanchion K is anchored to the curb, because this part of the curb 65 can be made low, so the cow will have plenty of throat room when lying with her head low down, and at the same time the sides of the curb may be made high enough to prevent the cow from nosing her feed out of 70 the manger at the sides on to the stall floor, as cows are liable to do.

Heretofore it has been difficult to make these cut-outs. The mold boards E either had to be cut away to correspond with the 75 cut-outs desired in the curbs, or the cut-out had to be formed with a trowel, either of which plans was expensive and unsatisfactory, and it required considerable labor and skill to do the work in an approved 80 manner or to produce cut-outs of standard shape and size. My cut-out form obviates this difficulty. The form can be readily made the proper size and shape and all that will be necessary is to set a number of them 85 in between the upper edges of the mold boards E at the proper places to make all the cut-outs in an extended curb of a uniform standard size and shape.

The upper edges of the board E should 90 be as high as the curb which is to be built between them. They should also be approximately straight and free from obstructions so the form A can be set at any desired point to form the cut-out between the 95 stall posts J. Fig. 3 represents a single stall section, but usually a number of stalls are placed in a row and the curbs for all of the sections are built at the same time or continuously as fast as the work can be 100 done. In such case the boards should be long enough to extend the entire length of the row of stalls, or a number of boards having their ends abutting to extend the entire length of the row of stalls.

105 A precise construction of the form A is not essential. It is only necessary that the forms shall be adapted to be set between and suspended by the boards E at the points necessary to form the cut-outs and that they 110 shall fill the upper portions of the spaces between the boards at these points. Usu-

ally a number of cut-out forms are employed simultaneously in the construction of a row of stalls, each form being set in its appropriate place to make a cut-out in the curb at that place.

5 In the form shown the ends of the cleats C are extended out beyond the sides S so they will rest upon the upper edges of the mold boards E and thus assist in holding the form in place. The stanchion anchors 10 can also be more accurately and securely set in the cement by attaching them to the bottom of the form A. The different figures show different styles of anchors which the forms can be arranged to hold while the cement is being placed. Figs. 1 and 2 show a U-bolt L which has its ends inserted in holes in the bottom of the form so as to hold it in place.

When the bottom board B is used, the upper 20 portions of the holes should be countersunk, as shown in Fig. 2, to let the nuts of the bolt L down to the proper position to hold the anchor loop O to which the stanchion is attached. When the bottom board 25 B is discarded and holes are made in the sheet-metal to receive the bolts, no countersinking is necessary.

Fig. 4 shows a different style of stanchion anchor P having bolts which are held in 30 the same way. Figs. 5 and 6 show still another style of stanchion anchor M which has a hook at its upper end. When an anchor of this kind is used, a slot is cut in the bottom of the form, and a key or pin N 35 is used to hold the hook in place.

When the cement is hard enough to remove the mold boards, the nuts are taken off the anchor bolts shown in Figs. 1, 2, and 3, and the key N is removed from the hook 40 of the anchor shown in Figs. 5 and 6. When this is done, the form A will be lifted out and the anchors will remain embedded in the cement. The bottom of the form may be provided with other means to hold different 45 styles of anchors to suit requirements. When the forms are removed, the loop O or other means for attaching the stanchion may be connected to the anchor.

The device is extremely simple and is 50 thoroughly effective in saving labor and insuring the best of work. The lower ends of the stall posts which are set in the curb H are represented by the letters J.

What I claim is:

55 1. In a mold for manger curbs having two parallel mold boards vertically set edgewise and spaced apart to suit the thickness of the

curb to be built, a core member to place between the mold boards and fill the space at a certain point between their upper edges, 60 said core member comprising spaced apart sides and a sheet metal bottom, and laterally projecting parts on the core member to rest on the upper edges of the mold boards.

65 2. In a mold for manger curbs, two parallel mold boards spaced apart to suit the thickness of the curb to be built, and a core member between the upper portions of the mold boards adapted to fill the space between them, said core member comprising two side boards and a sheet-metal bottom and having cleats with projecting ends to rest on the upper edges of the mold boards.

70 3. In a mold for manger curbs, two parallel mold boards spaced apart to suit the thickness of the curb to be built, and a core member between the upper portions of the mold boards adapted to fill the space between them, said core comprising two side 75 boards and a sheet-metal bottom, and having laterally projecting parts to rest on the upper edges of the mold boards, said bottom being adapted to support a stanchion anchor on the under side of the core member while the plastic cement is being placed between the mold boards.

80 4. A mold for forming cement manger curbs in permanent position, comprising two opposed substantially parallel boards 90 lying in substantially vertical planes, and placed apart a distance corresponding to the thickness of the manger curb, said boards having substantially horizontal upper and lower edges, the space between said boards 95 being uninclosed at the bottom whereby the boards can be readily lifted away from manger after the cement is in place, and a core member fitting between the upper portion of said boards, said core member being hollow and comprising two spaced side members each lying against one of the boards, and a bottom member joining the lower edges of the sides and constituting an open 100 top core, said bottom member being provided with means for supporting a stanchion anchor on the under side thereof, while the plastic cement is being placed between the mold boards whereby said anchor will be embedded in said cement.
